Des. 228,119
Patented Aug. 14, 1973

228,119

INSERT HOLDER SUPPORT DEVICE

Robert N. Cox, Cranbury, N.J., assignor to
Stamco Industries, Belleville, N.J.

Filed Feb. 18, 1972, Ser. No. 227,707

Term of patent 14 years

Int. Cl. D8—08

U.S. Cl. D8—254

FIG. 1

FIG. 2

FIG. 3

FIG. 4

FIG. 5

FIG. 1 is a side elevational view of an insert holder support device showing my new design;

FIG. 2 is a top plan view thereof;

FIG. 3 is a front isometric view;

FIG. 4 is a rear elevational view, and

FIG. 5 is a side elevational view of a modified form of the design in FIG. 1.

I claim:

The ornamental design for an insert holder support device, substantially as shown and described.
